Primary Examiner — Patricia A Palasik(74) *Attorney, Agent, or Firm* — Ladas & Parry LLP(57) **CLAIM**

The ornamental design for an intelligent service robot, as shown and described.

DESCRIPTION

FIG. 1 is a first perspective view of an intelligent service robot in accordance with the present invention;

FIG. 2 is a second perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a third perspective view of thereof.
